UNITED STATES PATENT OFFICE.

LESLIE E. HOOKER, OF LOWELL, MASSACHUSETTS.

MACHINE FOR MAKING CARTRIDGE-SHELLS.

1,352,194.

Specification of Letters Patent.

Patented Sept. 7, 1920.

Application filed April 6, 1918. Serial No. 227,026.

To all whom it may concern:

Be it known that I, LESLIE E. HOOKER, a citizen of the United States, residing at Lowell, in the county of Middlesex and State of Massachusetts, have invented new and useful Improvements in Machines for Making Cartridge-Shells, of which the following is a specification.

My invention relates to the manufacture of small cartridge shells, or other small closed-end tubes, by the method of extrusion which forms the subject matter of my prior Patent No. 922,585, of May 25, 1909. It consists in certain improvements which I have made to the machine for carrying out the said method, which machine forms the subject matter of my prior Patent No. 918,154, of April 13, 1909.

As far as the actual extruding operation is concerned, the means employed does not differ from that disclosed in my last mentioned prior patent, that is to say, the die and punches are the same, the present improvements relating to the automatic feed of the blanks and the automatic shifting of the punches in time with the strokes of the press.

As in the prior machine, the operation of making the rudimentary shell, or tube, is performed in two steps, the first being that of extruding the cup-shaped blank into a tube and the second being a so-called trimming step, which separates the extruded tube from the thin flange or fin which holds it in the die in which it was extruded, thereby freeing the tube and permitting it to drop out of the die.

In the prior machine, two identical extruding dies were used and one extruding punch and one trimming punch, which worked alternately in each die but, in the present machine, only one die is used with one extruding and one trimming punch, said punches being carried by a slide which reciprocates horizontally on the lower end of the press plunger so as to bring said punches alternately in line with the die at each down stroke of the plunger. To increase the output of the machine and to enable it to extrude a tube at each down stroke, two slides are provided, each carrying a pair of punches, and two dies, one slide moving forwardly while the other is moving backwardly. The blanks are fed, by any desired automatic feeding mechanism, successively into a pocket located at the

same distance from the die toward the front as the distance of the trimming punch behind the extruding punch, and are picked up by the extruding punch on the same stroke of the plunger as that on which the trimming punch acts, while, on the next stroke, the trimming punch is idle and the extruding punch performs its operation in the die on the blank which it picked up on the previous stroke. The operations of the punches in the other slide alternate with those of the punches in the first slide, as stated. The cup-shaped blank are previously given a quasi-polygonal internal shape so that they will be picked up with certainty and be accurately centered on the extruding punch.

With this preliminary general statement of the operation of the machine, it will now be described specifically with reference to the accompanying drawings, in which,

Figure 1 is a longitudinal sectional view through one of the dies and the corresponding punch slide, showing the blank feeding means and the slide operating means, the slide being in its most advanced and lowest position.

Fig. 2 is a similar view showing the slide in its highest position.

Fig. 3 is a similar view showing the slide in its most retracted and lowest position.

Fig. 4 is a plan view of the die-plate and blank feeding means.

Fig. 5 is a plan view of one of the cup-shaped blanks.

Fig. 6 is a vertical section of the same.

Fig. 7 is a view similar to Fig. 1 but on a larger scale and showing the punches and blank in section.

Fig. 8 is a view similar to Fig. 3, but on a larger scale and showing the punches and blank in section, the blank-feeding and the slide-operating means being omitted in the last two views, and

Fig. 9 is a front end view of the essential parts of the machine.

The machine employed is an ordinary straight-side die-shaping press, modified to enable it to perform the desired operations.

1 represents the anvil or bed-plate and 2 the reciprocating head or plunger, 3 representing the connecting-rod running to the crank-shaft 4, journaled in the standards 5, between which the plunger is guided, as usual. On the anvil 1 is mounted the die-plate 6 and on the latter the die-holder 7, contain-

ing the dies 8, which comprise the bushings 9 and are similar in every respect to the dies of the machine of my Patent No. 918,154 aforesaid. The die-holder 7 also contains 5 the yielding blocks 10, which constitute the bottoms of the pockets into which the blanks are successively fed and from which they are picked up by the extruding punches, as will be described.

10 Slidably mounted in horizontal guides 11, secured to the bottom of the plunger 2, are the punch-carrying slides 12, each having one extruding punch 13 and one trimming punch 14. As in my prior machine patent, 15 the extruding punch consists of a former 15 and a surrounding extruding sleeve 16.

The slides 12 are reciprocated in time with the strokes of the plunger by cams 24, fast on the cam-shaft 21, journaled in brackets 20, bolted to the standards 5, and carrying a sprocket wheel 22, driven from the crank-shaft 4 by a chain 23; the diameters of the sprocket wheels on the cam-shaft and crank-shaft are so selected that the crank-shaft turns twice as fast as the cam-shaft. 25 Each slide is formed at its rear end into a rectangular yoke 17, provided on its inner vertical faces with wear plates 18, 18', the latter being adjustable to take up wear by means of the wedge-shaped backing piece 19. 30 The active face of the cam is an arc the chord of which is equal to the distance between the wear plates. At each descent of the plunger, one of the slides is in its most 35 forward position and the other is in its most rearward position. When in the rearward position, the extruding punch acts upon the blank and the trimming punch is idle, while in the forward position, the trimming 40 punch acts upon the extruded tube to free it from the die while the extruding punch picks up the next blank.

A blank is illustrated in Figs. 5 and 6 at 25; it forms the subject matter of my 45 application for patent filed April 10, 1918, Ser. No. 227,690. It has a plurality of equally-spaced flattened surfaces 26, which are connected by arcs 27 of the original internal periphery. The extruding punch, in 50 picking up the blank, contacts, of course, only with said surfaces with which it firmly engages and which act to center the blank upon the punch so that it will be properly presented to the die.

55 The blanks are fed to the point where they are picked up by the punch by a suitable feeding mechanism, comprising as shown a rotating dial plate 28, partially surrounded by a fixed wall 29 and lying beneath fixed 60 guides 30 and 31, by which the blanks, which may be placed on the dial plate by hand but are preferably automatically fed thereto by one of the well known blank feed mechanisms, are guided into and along the guide- 65 ways 32 until they arrive successively in the

pockets 38, composed of the stop-plates 33, mounted on the die-holder 7, the endpiece 34 of the guides 31, and the spring fingers 35. The bottom of the pocket 38 consists of the yielding block 10, above mentioned, slidably mounted in the bushing 36 and pressed upwardly by the spring 37, its upward movement being limited by a shoulder on the block contacting with the bottom of the bushing, the opening in which is slightly 75 smaller than that in the die-plate. These yielding bottoms to the pockets prevent breakage in case the ends of the cup-shaped blanks vary in thickness. The die-holder 7 is provided with an opening 39 to receive 80 the trimming punch during its idle stroke, as shown in Fig. 3.

The operation can be understood from what precedes but may be briefly restated as follows:

85 The plunger descends with one of the slides 12 in the forward position of Fig. 1; the extruding punch enters the blank which has been fed into the pocket 38 while the trimming punch clears the previously extruded tube 40 from the die; the plunger rises and descends again with the slide in the rearward position of Fig. 2; the extruding punch carries the blank into the die and extrudes it into the tube 40, while the trimming punch passes idly into the opening 39. 90 The operations of the punches in the other slide alternate with those described.

Having thus described my invention, what I claim is:

1. A machine for extruding tubes from cup-shaped blanks, comprising the combination, with the die-holder and reciprocating plunger, of a slide guided on the bottom of the plunger, a cam for reciprocating said slide, means to drive said cam in timed relation with the plunger, an extruding punch and a trimming punch carried by said slide, a die mounted in said die-holder, and a pocket into which the blanks are fed successively and from which they are lifted by the extruding punch.

101 2. In the machine of claim 1, the die-holder containing two dies, a punch carrying slide for each die, and a cam for each slide, a shaft on which the cams are mounted, driving connections to said shaft from the crank-shaft which reciprocates the plunger such that the cam-shaft makes one half as many rotations as the crank-shaft, and 106 the two cams being set 180° apart, whereby, at each down stroke of the plunger, a tube is extruded, another is freed from the die, and a blank is picked up.

111 3. In a machine of the class described, 12 the combination with a fixed die and a reciprocating punch, of a positioning stop for the blanks to be operated on, and means to move the punch laterally to its reciprocating motion, so that it alternately descends in 13

line with the die and in line with a blank positioned by said stop.

4. In a machine of the class described, the combination of a die-plate, a die held thereon and a blank positioning stop fixed with relation to said die, a reciprocating plunger and a punch carried thereby, and means to move said punch on said plunger

at right angles to its reciprocating movement, whereby the punch descends alternately in line with said die and with said blank-positioning stop. 10

In testimony whereof I have hereunto set my hand.

LESLIE E. HOOKER.
